UNITED STATES PATENT OFFICE

RUFUS KING, OF PLAINVILLE, MASSACHUSETTS, ASSIGNOR TO BUGBEE & NILES COMPANY, OF NORTH ATTLEBORO, MASSACHUSETTS

BRACELET CONNECTION

Application filed February 18, 1932. Serial No. 593,703.

This invention relates to bracelet connections, and the primary object thereof is to provide an improved and simplified connection for the two ends of a bracelet, which connection is adjustable and which can be easily and quickly manipulated in the adjustment thereof.

The invention further aims to provide a connection of this type which can be made without the use of solder and which involves a minimum of parts which can be easily and quickly assembled.

In the drawings:

Figure 1 is a top plan view of the invention;

Figure 2 is a top edge view partly broken away, and in section;

Figure 3 is a bottom plan view showing the connector in open position;

Figure 4 is a detail plan view of the catch; and

Figure 5 is a section on line 5—5 of Figure 1.

In proceeding in accordance with the present invention a body member 1 is provided which is formed of a sheet of metal of substantially rectangular form having its opposite sides turned inwardly as indicated at 2 in Figure 5 to form a pair of spaced opposed 30 or confronting guides. One of the guides is formed with a series of spaced notches 4 providing keepers for a latch member 5. The latch as shown in Figure 4 is of substantially U-shape and has one end 6 turned inwardly to provide a supporting arm which slides on the bottom 3 of the member 1 while its opposite end is turned outwardly as indicated at 7 to provide a catch or finger 7 which latter is engageable with a selected one of the 40 keepers 4. A cover 9 is hinged at 8 to the body 1 and has its free end formed with a snap catch 11 and a finger engaging projection 10, the snap catch being formed to snap into engagement with a keeper 12 which latter is formed by an extension at the opposite end of the body 1 which extension is curled or rolled inwardly to form the keeper 12. As shown in Figures 2 and 3 the hinge 8 is spaced from the adjacent ends of the 50 guides 2 so as to receive in such space an end

of the link A at one end of the bracelet, the link B at the opposite end of the bracelet being connected to the closed end the catch 5.

With the parts in the position of Figure 3 it will be seen that the link A can be threaded over the cover 9 whereupon the cover is moved to the closed position shown in the Figure 1 with its catch 11 engaged with the keeper 12. When it is desired to adjust the spaces between the links A and B at the ends of the bracelet it is merely necessary to press inwardly on the finger or catch 7 to move same out of the keeper following which the member 5 is slid to the desired extent after which the catch 7 will then snap into engagement with one of the adjacent keepers 4, whereupon the device is automatically latched in its adjusted position.

The arm 6 acts as a stabilizing bearing for the catch 5 to afford easier adjusting movements thereof. From the foregoing it will be seen that the entire structure is composed of but four parts, namely the body, the cover, the catch member 5, and the pintle 75 of the hinge 8, all the parts being susceptible of metal stampings and manufacture and can be easily and quickly assembled and like manipulated in the various operations which the invention aims to provide.

As shown particularly in Figures 1 and 5 the cover 9 engages the inner side edges of the guides 2 and lies substantially flush therewith so that a smooth construction is had eliminating obviously objectionable projections.

It will furthermore be seen that due to the spacing of the ends 6 and 7 of the latch member 5 the link B can be easily and quickly threaded into engagement with the latch member.

Having thus described my invention what I claim as new and desire to secure by Letters Patent is:—

1. In a bracelet connector, a member having sides which are turned inwardly to form guides and having an end which is curled to form a keeper, a cover hinged to the member opposite the keeper and having a catch to engage the latter, one of the guides having

a series of spaced openings, and a substantially U-shaped latch member having its sides engaged in the respective guides and having one of its ends turned inwardly at an angle to form a stabilizer for engagement with the inner face of the body and having its opposite end turned outwardly to form a catch for selective engagement in the openings.

2. In a bracelet connector, a member having sides which are turned inwardly to form guides and having an end which is curled to form a keeper, a cover hinged to the member opposite the keeper and having a catch to engage the latter, one of the guides having a series of spaced openings, and a resilient latch having parts received in the respective guides and having a latching finger engageable through a selected one of the openings.

3. A bracelet connector composed of a body having spaced guides and having a keeper, a cover hinged to the body and having a catch to engage the keeper, a series of spaced keepers along one side of the guides on the body and a substantially U-shaped latch member having its sides engaged with the guides, and having one end turned outwardly to form a latching finger which is engageable with a keeper of the series of keepers.

4. In a bracelet connector, a body having spaced opposed guides, a cover hinged to the body at a point spaced from the guides so as to afford a space between the guides and the hinge to receive a link, said cover being received in the space between the guides and lying substantially flush therewith, means to latch the cover to the body, keepers carried by the body and a link engaging catch member having parts slidable in the guides and having a finger engageable with the keepers.

In testimony whereof I have signed my name to this specification.

RUFUS KING.
